DESIGN FOR A CAKE SAFE

William Garten, Baltimore, Md., assignor to
Owens-Illinois Can Company, Wilmington,
Del., a corporation of Delaware

Application October 4, 1938, Serial No. 80,250

Term of patent 7 years

To all whom it may concern:

Be it known that I, William Garten, a citizen of the United States, residing at Baltimore, in the State of Maryland, have invented a new, original, and ornamental Design for a Cake Safe, of which the following is a specification, reference being had to the accompanying drawing, forming a part thereof.

The figure is a perspective view of a cake safe showing my new design. The surface ornamentation is continuous around the article.

I claim:

The ornamental design for a cake safe, substantially as shown and described.

WILLIAM GARTEN.
